UNITED STATES PATENT OFFICE.

WILLIAM K. STEVENS, OF MANSFIELD, OHIO.

FEED-WATER PURIFIER.

SPECIFICATION forming part of Letters Patent No. 293,537, dated February 12, 1884.

Application filed August 3, 1883. (No model.)

To all whom it may concern.

Be it known that I, WILLIAM K. STEVENS, of Mansfield, in the county of Richland and State of Ohio, have invented certain new and 5 useful Improvements in Feed-Water Purifiers, of which the following is a specification.

My invention relates to apparatus for heating and for removing the impurities from feed-water for steam-boilers; and it consists of certain devices for the heating and purifying of the water under pressure while in transit from the feed-pump to the boiler, all of which will be fully described hereinafter.

In the accompanying drawings, in which 15 similar letters of reference indicate similar parts, Figure 1 is a front elevation of a steam-boiler, showing my improvement attached thereto. Fig. 2 is a partial elevation and partial section of the parts shown in Fig. 1. Fig. 20 3 is a plan of Figs. 1 and 2. Fig. 4 is a plan of the lead strainer; Fig. 5, a sectional elevation, and Fig. 6 a bottom plan, of the filter-chamber.

A is a steam-boiler of any approved type; 25 B B', steam-pipes leading from boiler A to precipitating-chambers C C', and provided, respectively, with valves b b'.

D is the line of feed-pipe through which the 30 feed-water is delivered to the first precipitating-chamber, C.

c and c' are heads to the precipitating-chambers C C', where the condensation of the steam and heating of feed-water takes place.

c' is a bent pipe of relatively large diameter, 35 connecting the bottom of chamber C with top or head c' of chamber C', (the chamber C being arranged relatively above chamber C', in order that the contents of the former may flow by gravity into the latter.)

E is a down-pipe, connecting, by means of 40 pipe e, the bottom of chamber C with the lower portion of filter-chamber F.

F' is the filter-shell, mounted upon legs f within the chamber F, and provided with a 45 perforated bottom, f', of wire-cloth.

G is a mass of lump coke completely filling the filter-shell F', and surmounted by a heavy 50 perforated disk of lead, H.

F² is the lid or cover of filter-chamber F, 55 which is hinged and secured to flange of cham-

ber by means of bolts and nuts, in the usual manner. The covers c' c' of precipitating-chambers C C' are also hinged, as shown in Fig. 2, and secured to the flanges of the respective chambers by bolts and nuts, in the manner customary with work of this character. 55

D' is a continuation of the feed-pipe, connecting the upper part of filter-chamber with the lower part of the boiler A, and provided with a valve, d.

e is the blow-out pipe, controlled by valve e', by means of which the filter-chamber F may be purged of the heavy residuum.

The operation of the apparatus is as follows: The feed-pipe D, precipitating-chambers C C', 60 down-pipe E, pipe e, filter-chamber F, and pipe D' being full of water at boiler-pressure, and in transit toward the boiler by the impulse of any approved form of feed-pump, steam is admitted from the boiler A through 70 pipe B into chamber C, and by pipe B' into chamber C'. The live steam, flowing into the precipitating-chambers, heats the feed-water to any desired temperature within the corresponding temperature of the steam at boiler-pressure, and precipitates upon the walls and bottom of these chambers the impurities—as carbonate of lime—in solution in the water.

The water, freed from the most objectionable salt in solution, passes downward from the 75 lower precipitating-chamber, C', through pipe E, and thence into the filtering-chamber F by means of connecting-pipe e, thence upwardly through the wire-gauze strainer f', coke G, and perforated lead disk H, and finally through 80 feed-pipe D' to the boiler A. The passage of the water upward through the filtering-chamber F' removes all the heavy matter in suspension and delivers it to the boiler, practically free from any injurious impurities. 85

I am aware that feed-water heaters and purifiers which perform the triple office of removing the principal salts in solution, filtering from the water the matter in mechanical suspension, and finally heating the water approximately to the boiling-point are not new, and that my invention is limited to the devices substantially as shown and described. The amount of live steam requisite for the precipitating of the salts in solution is suffi- 90 95 100

cient to elevate the temperature of the feed-water nearly or quite to the boiling-point, and the water is thereby delivered to the boiler A in the best possible condition for economy.

5 Having described my invention, what I claim is—

1. In combination with the boiler A, feed-pipe D D', and steam-pipes B B', the two precipitating-chambers C C' c c', and connecting-pipe c², when arranged and operating substantially as and for the purpose described.
- 10 2. The combination of boiler A, the two precipitating-chambers C C' c c', the filter-

chamber F, containing the shell F', provided with the perforated bottom f, perforated lead 15 disk H, and intermediate filtering material, and the several connecting-pipes, substantially as described.

In testimony whereof I have signed my name to the foregoing specification in the presence 20 of two subscribing witnesses.

WILLIAM K. STEVENS.
